GESELLSCHAFT, OF ESSEN-ON-THE-RUHR, GERMANY.

PIVOT-GUN.

1,373,962.

Specification of Letters Patent.

Patented Apr. 5, 1921.

Application filed September 4, 1920. Serial No. 408,404.

To all whom it may concern:

Be it known that I, KURTH HALLER, residing at Essen, Germany, a citizen of the German Republic, have invented a certain 5 new and useful Improvement in Pivot-Guns, of which the following is a specification.

This invention refers to a pivot gun, the gun barrel of which is mounted permanently outside a covered chamber hermetically sealed on all sides, and which gun can be sighted and laid from the interior of this chamber.

The invention will be described with reference to the accompanying drawing, which shows a vertical section of the gun together with parts of the covered position.

Through an opening in the upper face of cover A, which shuts the inner chamber B of the covered position off from the outside, projects the pedestal mounting C of the gun, which is rigidly attached to the cover A, and between which cover A and a flange c¹ on the pedestal C is placed a packing. The 25 upper carriage D of the gun can rotate relatively to the pedestal C about the axis of the hollow pivot pin d¹ mounted thereon and which upper carriage is carried in the upper part of the pedestal C and an extension 30 of the pedestal, which surrounds the middle portion of the pivot pin. The extension c² of the pedestal C, which passes through a lid a¹ inserted in the cover A, and the pivot pin d¹, which projects downward 35 beyond the extension c², project into the covered chamber B. The pivot pin d¹ is packed in the extension c² of the pedestal by a stuffing box d². Lugs (d³), which grip under a flange c³ on the pedestal C, prevent the 40 upper carriage from being lifted off the pedestal. The gun barrel E is mounted in the upper carriage by means of horizontal trunnions (e¹).

The gun barrel is elevated by turning a 45 hand wheel F, the horizontal shaft f¹ of which is mounted in a bracket d⁴ on the lower end of the pivot pin d¹ and the rotation of which shaft f¹ is transmitted by a pair of bevel wheels f² f³ to a hollow shaft F⁴ mounted in the pivot pin d¹. This shaft F⁴, the axis of which coincides with the axis 50 of the pivot d¹ is packed on the pivot pin by stuffing boxes f⁵ f⁶. The end of shaft F⁴, which projects between the walls of the upper carriage D carries a bevel wheel f⁷ which gears

with a bevel wheel f⁸. On the horizontal shaft f⁹, which carries the bevel wheel f⁸ and which is mounted in the upper carriage D is mounted a worm f¹⁰, which gears with a toothed sector e² attached to the gun barrel E.

The elevation imparted to the gun barrel by means of the gears described can be read off by the gun layer on an elevation indicating disk F¹¹, which is arranged in the chamber B and provided with a fixed pointer f¹². The disk F¹¹ is driven independently of the pinion gearing of the elevating gear from the gun barrel, by means of a toothed sector e³ mounted on the gun barrel E, which gears with a toothed wheel f¹³ mounted on the upper carriage D, the rotation of which is transmitted by a pair of bevel wheels f¹⁴ f¹⁵ to a shaft f¹⁶ mounted in the hollow shaft F⁴ and packed therein 70 by stuffing boxes f¹⁶ f¹⁷. To the shaft f¹⁶ is positively connected the disk F¹¹ by three pairs of bevel wheels f¹⁸ f¹⁹ and f²⁰, the shafts of these gears being carried in the bracket d⁴.

The traversing gear is driven by a hand wheel G, the rotation of which is transmitted by two pairs of bevel wheels g¹ g² to a worm g³, which gears with a worm wheel c⁴ fixed on the extension c² of the pedestal. Bearings d⁵ are provided on the pivot pin d¹ for the shafts of the parts G g¹ g² g³ of the gearing. When the hand wheel G is rotated, the worm g³ travels over the fixed worm wheel c⁴, so that the upper carriage 90 D and the gun barrel E can be rotated about the axis of the pivot c² d¹ by means of the pivot pin d¹.

The traverse imparted to the gun barrel can be read off on a traverse indicating disk G⁴ by the aid of a fixed pointer g⁵. The shaft g⁶ which carries the said disk G⁴ and rotates in bearings d⁵, carries a toothed wheel g⁷ which gears with a toothed wheel c⁵ mounted on the extension of the pedestal c² and travels over it when the pivot pin rotates.

Through the hollow chamber of the pivot pin d¹ are passed in addition to the shaft F⁴ electric cables H for the firing mechanism and other purposes, these cables being packed at the point where they enter the pivot pin by a stuffing box h¹ and at the point where they leave it by a stuffing box h².

The arrangement described is first characterized by the fact, that the stuffing box d^2 , which packs the rotating pivot pin d^1 in the stationary extension of the pedestal c^2 5 lies inside the covered chamber B. This stuffing box can therefore be constantly watched by the gun crew and if necessary be tightened up. Furthermore the whole of the pinion gearings of the traversing gear 10 and the indicating apparatus corresponding thereto G^4 g^5 as well as the important parts of the elevating gear together with the indicating apparatus are contained in the covered chamber B and are therefore protected 15 against external influences. An additional advantage of the arrangement consists in the fact that the gun is built up complete outside the mounting and can be placed in the position prepared for it as a whole.

20 Claims.

1. An arrangement of the class described comprising a pivot gun, a carriage therefor, a closed chamber, said chamber being provided with an opening, a pedestal projecting 25 from said opening, a hollow pivot pin forming the axis for said gun carriage, said pivot pin being supported by said pedestal, an extension on said pedestal projecting into the chamber and surrounding said pivot 30 pin, means for packing the pivot pin in the extension, means operatable from within the chamber and extending through said pivot pin for elevating the gun and means operatable from within the chamber for rotating the pivot pin for traversing the gun.

2. An arrangement of the class described comprising a closed chamber, said chamber being provided with an opening, a lid for said opening, a pedestal projecting from 40 said chamber, a pivot gun, a carriage therefor, an elevating mechanism on said carriage, a hollow pivot pin supporting said carriage and forming an axis therefor, said pivot pin being supported by said pedestal 45 and projecting through said lid to the interior of the chamber, means operatable from within said chamber and extending through the hollow pivot pin for operating the elevating mechanism and means also 50 operatable from within said chamber for rotating the pivot pin to traverse the gun.

3. An arrangement of the class described comprising a closed chamber provided with an opening, a cover for said opening, a pivot gun, a carriage therefor, an elevating mechanism supported on said carriage, a pedestal projecting from the opening of the chamber, a hollow pivot pin rotatably supported 55 on said pedestal, carrying said gun carriage 60 and forming an axis therefor, said pivot pin projecting into said chamber, an extension on said pedestal extending into said chamber, and surrounding the pivot pin, means for packing said pivot pin in said pedestal 65 extension, means carried by the inner end of

said pivot pin and projecting through the center thereof for operating the gun elevating mechanism and means carried by said pivot pin for rotating the same to traverse the gun.

4. An arrangement of the class described comprising a closed chamber provided with an opening, a cover for said opening, a pivot gun, a carriage therefor, an elevating mechanism supported on said carriage, a pedestal 70 projecting from the opening of the chamber, a hollow pivot pin rotatably supported on said pedestal, carrying said gun carriage and forming an axis therefor, said pivot pin projecting into said chamber, an extension 75 on said pedestal extending into said chamber, and surrounding the pivot pin, means for packing said pivot pin in said pedestal extension, means carried by the inner end 80 of said pivot pin and projecting through the center thereof for operating the gun elevating mechanism and a worm wheel fixed to the pedestal extension and means carried by the inner end of the pivot pin and co-operating therewith for rotating the pivot 85 pin to traverse the gun.

5. An arrangement of the class described comprising a closed chamber, said chamber being provided with an opening, a lid for 90 said opening, a pedestal projecting from 95 said chamber, a pivot gun, a carriage therefor, an elevating mechanism on said carriage, a hollow pivot pin supporting said carriage and forming an axis therefor, said pivot pin being supported by said pedestal 100 and projecting through said lid to the interior of the chamber, means operatable from within said chamber and extending through the hollow pivot pin for operating the elevating mechanism, means also operable 105 from within said chamber for rotating the pivot pin to traverse the gun, indicating devices for indicating the elevation and traverse imparted to the gun barrel, means for supporting said indicating devices upon the lower end of said pivot pin and means independent of the elevating and traversing mechanism for operating the indicating devices.

6. An arrangement of the class described 115 comprising a closed chamber provided with an opening, a cover for said opening, a pivot gun, a carriage therefor, an elevating mechanism supported on said carriage, a pedestal projecting from the opening of the chamber, a hollow pivot pin rotatably supported 120 on said pedestal, carrying said gun carriage and forming an axis therefor, said pivot pin projecting into said chamber, an extension on said pedestal extending into said chamber, and surrounding the pivot pin, means for packing said pivot pin in said pedestal 125 extension, means carried by the inner end of said pivot pin and projecting through the center thereof for operating the gun elevat- 130

ing mechanism, means carried by said pivot pin for rotating the same to traverse the gun, a device for indicating the elevation imparted to the gun barrel, a device for indicating the traverse imparted to the gun barrel, said indicating devices being supported by the end of the pivot pin which projects into said chamber, means independent of the elevating means for connecting the first mentioned indicating device to

the gun barrel and means independent of the traversing means for connecting the second mentioned indicating device to the pivot pin.

The foregoing specification signed at 15
Essen, Germany, this 10th day of June, 192^r
